[57] CLAIM

The ornamental design for a storage rack, as shown and described.

DESCRIPTION

FIG. 1 is a top plan view of a storage rack showing my new design;

FIG. 2 is a front elevational view thereof, the rear elevational view thereof being a mirror image;

FIG. 3 is a left side elevational view thereof, the right side elevational view thereof being a mirror image;

FIG. 4 is a bottom plan view thereof; and,

FIG. 5 is a perspective view thereof.

The storage rack is used to hold compact disks, and tape cassettes.
